MACHINE FOR COATING GOLF BALLS OR
THE LIKEChester W. Haynes, Springfield, Mass., assignor
to The Fisk Rubber Corporation, Chicopee Falls,
Mass., a corporation of Delaware

Application June 27, 1938, Serial No. 215,975

13 Claims. (Cl. 91—46)

This invention relates to a machine for coating or painting golf balls and similar articles.

Among the objects of my invention is the provision of a device of this character by means of which a plurality of balls may be coated simultaneously in a uniform manner and without waste of the coating material.

Other and further objects will be apparent from the following specification and claims.

In the accompanying drawings which illustrate one embodiment of my invention—

Fig. 1 is a plan view of a painting machine constructed according to my invention, parts being broken away to better show the construction;

Fig. 2 is a side elevational view of the structure shown in Fig. 1, parts being broken away;

Fig. 3 is a view similar to Fig. 2 but showing the operating parts in their initial position at the start of a cycle of operation;

Figs. 4 and 5 are detail views showing subsequent positions of the carriage and the ball handling parts carried thereby;

Figs. 6, 7, and 8 are detail side views showing successive positions of the ball gripping fingers;

Figs. 9 and 10 are detail side views of the ball feeding mechanism;

Fig. 11 is a sectional view of the coating tank; and

Figs. 12 and 13 are detail sectional views of the rack moving parts.

Referring to the drawings, 10 indicates a rectangular frame by which the operating parts are supported. As shown in Figs. 1 and 2, the machine includes a hopper feeding means generally indicated at 11, a reciprocating carriage 12 which receives a row of balls from the hopper, dips them in a coating tank 13 and delivers them to receiving racks 14 supported by a frame 15 positioned at the rear end of the machine.

Fig. 3 shows the parts at the end of a cycle of operation and ready for the start of the succeeding cycle.

The carriage 12 comprises side members formed of bearings blocks 17 connected by bars 18 and 45 slidably mounted on rods 19 supported on four posts 20 secured to frame 10. End rods 21 (Fig. 1) connect the end posts to give rigidity to the carriage support. A shaft 24 extending transversely of the machine is rotatably supported at 50 its ends in bearings 25 formed in the carriage side members.

Brackets 26 and 27 are rigidly secured to the shaft 24 inwardly of the bearings 25 (see Fig. 1) and are connected by spaced parallel bars 28 which carry a plurality of sets of gripping fingers

between which the balls are individually engaged.

As best shown in Figs. 6, 7, and 8, the gripping fingers are arranged in groups of three, comprising a pair 30 and a single opposed finger 31. These fingers are fixed in respective blocks 32 pivoted on pivot pins 33 fixed in the bars 28. Fingers 30 are urged toward finger 31 by springs 35 secured at one end to the blocks 32 in which fingers 30 are mounted and connected at the other end to pivot pins 33 of finger 31. 10

The fingers 30 and 31 of the various groups are adapted to be moved toward and from each other simultaneously by cam actuated rods 38 and 39 slidably mounted in the end brackets 26 and 27 and intermediate brackets 40 (Fig. 1) secured to shaft 24. The rod 38 carries a plurality of collars 41 slotted as at 42 to receive pins 43 projecting from the blocks 32 in which fingers 31 are mounted. Rod 39 is similarly provided with collars 44 provided with projecting pins 45 engageable with 20 the inner faces of the blocks 32 in which fingers 30 are mounted. The rods 38 and 39 are actuated to open and close the gripping fingers 30 and 31 by a cam 47 against which the rod 38 is pressed by a spring 48 (see Fig. 1) positioned between 25 bracket 27 and a collar 49 secured to the rod. Similarly rod 39 is pressed against the cam by a spring 50 positioned between a collar 51, secured to rod 39, and the adjacent bracket 40. 25

As best shown in Figs. 3, 6, and 8, cam 47 is rotatably mounted on bracket 26 and is provided with an inclined cam groove 53, in which the end of rod 39 engages, and with an extended arcuate portion 54 engaged by rod 38. As will be seen in Fig. 6, when rod 39 is out of groove 53 and rod 38 engaged with the low portion of extension 54, the gripping fingers are held separated. When, as shown in Fig. 8, cam 47 is rotated approximately 180° from the position of Figs. 3 and 6, rod 38 rides on to the high portion of extension 54 and rod 39 enters groove 53, thus shifting the rods in opposite directions to move the fingers toward each other to grip a ball 60 shown in dotted lines. Cam 47 is provided with a handle 55 by which the cam may be rotated. 40

Shaft 24 is adapted to be rotated in its bearings, as later described, by means of a handle 56 secured to the end of the shaft. 45

Carriage 12 is adapted to be reciprocated along rods 19 by means of a lever 61 secured to the end 50 of a rock shaft 62 journaled in brackets 63 (Fig. 1) mounted on frame 10. A pair of arms 64 secured to shaft 62 are connected by adjustable links 65 to a rod 66 secured in the side members of carriage 12. The lever 61 is provided with a releas- 55

able spring actuated detent mechanism of any suitable form, indicated at 61, cooperating with notches 68 in a fixed segmental member 69 to define the various operative positions of the carriage, as later explained.

In Fig. 3 the carriage is at the end of its rearward stroke, and the fingers 30-31 are open, having just discharged a row of coated balls on rack 14.

As the initial operation of a cycle of operations the operator swings lever 61 to the right as viewed in the figures, to move the carriage from the position of Fig. 3 to the position shown in Fig. 4, in which the gripping fingers clear the receiving frame 15. Shaft 24 is then rotated 180° in its bearings to swing the fingers and the other parts supported by the shaft, including cam 47, to the position shown in Fig. 5. By means of lever 61 the carriage is moved to the extreme forward end of its stroke in which position the open fingers 30-31 pass between balls 60 arranged in a row on a loading platform 70 of hopper 11, as shown in Fig. 9. In this position, as shown in the latter figure, arm 53 of the finger-operating cam is in the path of a trip member 71.

As best shown in Fig. 1, the bottom of hopper 11 is grooved as at 72 to arrange the balls in longitudinal files, the grooves being extended onto the loading platform 70. Referring to Figs. 2, 9, 30 and 10, the hopper 11 is pivoted at 74 to spaced brackets 75 mounted on frame 10. Pivots 74 are positioned slightly off the center of gravity of the hopper toward the loading platform and the main portion of the hopper normally rests on a supporting member 76 (Fig. 2) which is made adjustable as at 77 so that the row of balls at the loading position on platform 70 may be adjusted vertically with respect to the gripping fingers. A shaft 78, rotatably mounted in brackets 75, carries a cam lug 79 adapted, when shaft 78 is rocked clockwise as viewed in Figs. 9 and 10, to engage the bottom of the hopper, and tilt the hopper as shown in Fig. 10. Shaft 78 is provided with an operating lever 80 formed with an extending portion 31 to which is connected one end of a link 82, the other end of which is connected to one member of a knuckle linkage 83 supported by a standard 84 and carrying a trip member 71.

With the parts in the position shown in Fig. 9, 50 in which as above described fingers 30-31 are in position between the leading row of balls on the loading platform, lever 80 is swung to the position shown in Fig. 10. The initial portion of the movement of lever 80 causes trip member 71 to engage handle 55 of the gripper operating cam 47 to rotate the latter and cause the fingers to engage the balls. Further movement of the lever 80 causes cam lug 79 to engage the bottom of the hopper and tilt the latter into the position shown 55 in Fig. 10, retracting the loading platform from ball supporting position and causing the files of balls in grooves 72 to advance and replace the row of balls which have been seized by and are now held suspended in the gripper fingers 30-31.

To assure proper feeding of the balls from the hopper a blade 90 is supported by depending arms 91, pivoted at their upper ends to the hopper at 92, in position to enter a slot 93 formed across the front of the hopper. Blade 90 is constrained to enter the slot 93 by springs 94 connecting the lower ends of arms 91 to the hopper at 95. When the hopper is in its normal or horizontal position, shown in Fig. 9, blade 90 is held outwardly of the slot 93 by hooks 96 engaging the adjacent end 75 rod 21 of the carriage supporting frame. As the

hopper tilts forward toward rod 21, blade 90 is permitted to enter the slot 93 under the action of springs 94, pushing the tier of balls overlying those in channels 72 away from the face of the hopper to prevent wedging or crowding of the balls and assuring that a complete complement of balls is at all times in loading position on the platform 70.

From the position of Fig. 10 the carriage 12 is moved to the position shown in Fig. 2 in which 10 the gripped balls are held suspended over coating tank 13.

Coating tank 13 is periodically raised, to immerse the balls as shown in Fig. 1, and then lowered, by continuously operating means best 15 shown in Figs. 2 and 11.

Tank 13 is provided adjacent its ends with downwardly extending posts 100, reciprocating in suitable guides not shown, and provided on their lower ends with rolls 101 resting on cams 102, secured to a shaft 103 journaled in depending brackets 104. Shaft 103 is constantly driven from a motor 105, the shaft of which is connected to a conventional gear reduction unit 106 to drive a shaft 107 carrying a sprocket 108. Sprocket 108 is connected by chain 109 to a sprocket 110 mounted on a countershaft 111 which carries a sprocket 112 connected by a chain 113 to a sprocket 114 secured to shaft 103 intermediate the cams 102.

The cams 102 are so contoured that the rising movement of the tank to immerse the balls as shown in Fig. 11 is relatively more rapid than the downward movement. The latter movement is so timed that as the balls slowly emerge, any surplus coating material flows from the emerging ball, leaving a uniform coating on the ball and preventing the accumulation of any substantial amount of coating material at the lower side of the ball as the latter finally leaves the coating liquid, gravity and the surface tension of the liquid in the tank both acting to draw the maximum of surplus material to the tank and from the ball at the break. As soon as the tank has cleared the balls, the operator rotates shaft 24 through an arc of 180° by means of handle 56 to bring the fingers 30-31 with their engaged balls to an upright position, thus reversing the position of the balls so that any excess of material on what had previously been the lower half of the ball spreads itself under the action of gravity.

During the dipping operation the operator restores the hopper operating lever to the position shown in Fig. 9 in readiness for the next cycle of operation, and also places a rack 14, see Fig. 1, 55 on the free ends of rack frame 15 at A, Fig. 2. As best shown in Fig. 1, the racks are cut away or notched along their forward edges to form a plurality of projections 120 positioned to pass between the gripper fingers and beneath the engaged balls. Portions 120 are provided with a plurality of short spikes 121, upon which the balls are deposited, as will be now described.

As soon as the fingers have been swung to an upright position, lever 61 is operated to move 65 the carriage to the position shown in Fig. 3, and the gripper fingers are separated by swinging cam operating handle 55 to the position shown in the latter figure. Upon their release by the gripper fingers the balls drop onto the spikes 121 70 of the rack and the parts are in position for the next cycle of operation.

The racks or trays 14 are preferably automatically moved rearwardly on frame 15 by means of pawls 123 pivoted to the free ends of arms 124 75

adjustably secured at 125 to rod 66 of the carriage. The length of arms 124 is made such that when the carriage is at the extreme right-hand end of its travel, as viewed in the figures, that is, 5 at the loading position of the grippers, the pawls 123 clear the end of the rack supporting frame 15. When the carriage moves from loading position to the coating position shown in Fig. 2 the pawls engage the previously loaded tray on the 10 end of the frame at position A and moves it rearwardly on the frame to position B, thus leaving room for the operator to place an unloaded tray at the end of the frame in position A while the dipping operation is in progress as previously 15 described. Movement of the carriage to discharge position as shown in Fig. 3, moves the previously loaded tray to position C. On the next advance of the carriage to loading position, pawl 123 is drawn beneath the newly filled rack at A in the manner shown in Fig. 13.

As will be clear from the drawings, the fingers 30-31 are pointed so that no discernible marks are left at their point of contact. It is desirable that the fingers be kept relatively free of paint and it is, therefore, desirable after a number of dippings to wash the fingers. For this purpose a washing tank 230 is provided. Tank 230 is supported on a pair of spaced posts 231 vertically slidable in the frame 10 and supported at their lower end on curved cam arms 232 secured to a rock shaft 233 rotatably mounted in hangers 234 secured to frame 10. The curved tank supporting arms 232 are normally maintained in lowered position by a spring 235 connecting an oppositely extending arm 236, secured to shaft 233, to frame 10. Arms 232 are adapted to be rocked to raise tank 230 into position to immerse and wash the gripper fingers by means of a foot treadle 237 pivoted to frame 10 at 238 and connected by a link 239 to the arm 236. A spring actuated catch mechanism 240 is provided to releasably engage the treadle 237 to hold the tank 230 temporarily in washing position.

I claim:

43 1. A device for coating golf balls or the like which comprises a ball feeding means, a ball coating means and a ball receiving means, a reciprocal gripping mechanism adapted to transport balls successively from said feeding means to the coating means and finally to the ball receiving means, means to reciprocate said gripping mechanism and means for rotating the gripping mechanism through an arc of substantially 180° from the coating position to deliver the balls in 50 reversed position to the receiving means.

55

33 2. A device for coating golf balls or the like
which comprises, a reciprocating carriage, grippers
on said carriage for releasably engaging the
balls to be coated, means to reciprocate the car-
riage, means at one end of the carriage travel
60 for feeding balls to the grippers, means at the
opposite end of the carriage travel to receive
the balls from the grippers, and means in the
path of travel of the carriage intermediate said
ball feeding and ball receiving means for im-
65 mersing the gripper held balls in a coating
liquid.

3. A device for coating golf balls or the like, which comprises, a reciprocating carriage, a grip-
70 per support rotatably mounted on the carriage, grippers mounted on said support for releasably engaging the balls to be coated, means at one end of the carriage travel for feeding balls to the grippers, means at the opposite end of the carriage travel to receive the balls from the grip-

pers, means in the path of travel of the carriage intermediate said ball feeding and ball receiving means for immersing the gripper-held balls in a coating liquid and means to rotate the gripper support through an arc of substantially 180° from the immersing position to deliver the balls in reversed position to the receiving means.

4. A device for coating golf balls or the like which comprises a gripper support mounted for rotation about a horizontal axis, opposed gripper fingers carried by said support and extending radially therefrom, said fingers being mounted on the support for movement toward and from each other, means for feeding balls into position to be engaged by the gripper fingers, a tank for coating liquid in which the gripper fingers are immersed in one position of rotation of the support, means to rotate the gripper support 180° from the immersing position, and means for moving the gripper fingers toward and from each other to respectively grip and release the balls.

5. In a device for coating golf balls or the like, spaced parallel rails, bearing members slidably mounted on said rails, a shaft rotatably mounted at its ends in said bearing members and forming with the latter a reciprocable carriage, a plurality of sets of opposed pivotally mounted gripper fingers supported on said shaft, cam actuated means for simultaneously swinging the opposed fingers of each set of gripper fingers toward each other to engage a plurality of balls, means to rotate said shaft in the bearing members to swing the grippers bodily from a depending position to an upright position, and cam means for separating the grippers to discharge the balls therefrom while the grippers are in an upright position. 235 20 235

6. In a device for coating golf balls or the like, a reciprocable carriage, opposed gripper fingers mounted on the carriage for movement toward and from each other, cam means for moving the gripper fingers, ball feeding means positioned in the path of carriage travel and including a loading platform adapted to support the balls in position to be embraced by the open gripper fingers as the carriage moves to loading position, means to retract the loading platform from ball supporting position and means operable to actuate said cam means to cause the grippers to engage the balls prior to the retraction of the loading platform. 40 45 50

7. In a device for coating golf balls or the like, a reciprocable carriage including a gripper support, opposed gripper fingers mounted on the support, said support being rotatably mounted on the carriage to permit bodily movement of the grippers through an arc of 180° from an upright to a depending position, means for opening and closing the gripper fingers, ball feeding means positioned in the path of the gripper fingers when the latter are in a depending position, said feeding means including a loading platform for supporting balls in a position to be gripped by the fingers and means operable to actuate the gripper fingers and thereafter retract said loading platform to leave the balls suspended in the gripper fingers. 55 60 65

leave the said support in the grip 70
8. In a device for coating golf balls or the like, a reciprocable carriage including a gripper support, rotatably mounted on the carriage, a plurality of sets of opposed gripper fingers mounted on said support for movement toward and from each other, a pair of rods slidably mounted in the support and respectively connected to the oppositely moving grippers of each set, a rotatable 75

- cam member for simultaneously sliding said rods in opposite directions for opening and closing the gripper fingers, ball feeding means adjacent one end of the path of carriage travel including a 5 loading platform adapted to support a series of balls in position to lie between the open fingers of the grippers in one position of rotation of the support, means operable to rotate the cam to close the gripper fingers and to thereafter retract the 10 loading platform to leave the balls suspended in the gripper fingers, and a ball receiving means positioned at the opposite end of the carriage travel to underlie the balls in the gripper fingers when said support is rotated substantially 180° 15 from its loading position.
- 16 9. In a device for coating golf balls or the like, a reciprocable carriage including a gripper support, rotatably mounted on the carriage, a plurality of sets of opposed gripper fingers mounted 20 on said support for movement toward and from each other, a pair of rods slidably mounted in the support and respectively connected to the oppositely moving grippers of each set, a rotatable cam for simultaneously sliding said rods in opposite 25 directions for opening and closing the gripper fingers, ball feeding means adjacent one end of the path of carriage travel including a loading platform adapted to support a series of balls in position to lie between the open fingers of the 30 grippers in one position of rotation of the support, means operable to rotate the cam to close the gripper fingers and to thereafter retract the loading platform to leave the balls suspended in the gripper fingers, and a ball receiving means 35 positioned at the opposite end of the carriage travel, said receiving means including a frame and a plurality of racks slidably supported thereon, said racks being provided with projecting portions extending between the gripper fingers and beneath the balls when the gripper support is rotated substantially 180° from its loading position, and pawl means connected to the carriage for advancing the racks along the frame as the carriage moves from loading to discharge position.
- 40 10. A device for coating golf balls or the like which comprises a reciprocating carriage, grippers on said carriage for releasably engaging the balls to be coated, means to reciprocate the carriage, ball feeding means adjacent one end of the carriage travel for supplying balls to the grippers, means adjacent the other end of carriage travel to receive the balls from the gripper, a dipping 45 tank for coating liquid positioned intermediate the ball feeding and ball receiving means, and

means to raise and lower the tank to immerse the gripper-held balls in the coating liquid.

11. A device for coating golf balls or the like which comprises a reciprocating carriage, grippers on said carriage for releasably engaging the 5 balls to be coated, means to reciprocate the carriage, ball feeding means adjacent one end of the carriage travel for supplying balls to the grippers, means adjacent the other end of carriage travel to receive the balls from the gripper, a dipping tank 10 for coating liquid positioned intermediate the ball feeding and ball receiving means, and means to raise and lower the tank to immerse the gripper-held balls in the coating liquid, said last-named means being operable to lower the tank at a relatively slower rate than its upward immersing movement so as to minimize any excess of coating material left on the low side of the emerging 15 balls.

12. A device for coating golf balls or the like 20 which comprises a reciprocating carriage, grippers on said carriage for releasably engaging the balls to be coated, means to reciprocate the carriage, ball feeding means adjacent one end of the carriage travel for supplying balls to the 25 grippers, means adjacent the other end of carriage travel to receive the balls from the gripper, a dipping tank for coating liquid positioned intermediate the ball feeding and ball receiving means, and means to raise and lower the tank to immerse the gripper-held balls in the coating liquid, said last-named means including a cam adapted 30 to time the upward and downward movement of the tank, so as to minimize any excess of coating material left on the lower side of the emerging 35 balls, and power means for driving the cam.

13. A device for coating golf balls or the like which comprises, a reciprocable carriage including a gripper support, opposed gripper fingers mounted on the support, said support being rotatably mounted on the carriage to permit bodily movement of the grippers through an arc of 180° from a depending position to an upright position, means for supplying balls to the grippers, a dipping tank for coating liquid, means for raising the 45 tank to immerse the balls in the coating liquid while the grippers are in a depending position and operable to thereafter lower the tank, and ball receiving means positioned to receive the balls from the grippers when the gripper support has 50 been rotated 180° to bring the grippers to upright position.

CHESTER W. HAYNES.
